Specification for Design.

Patented Dec. 12, 1911.

Application filed May 11, 1910. Serial No. 560,751. Term of patent 7 years.

To all whom it may concern:

Be it known that I, DENNIS A. DRISCOLL, a citizen of the United States, residing at Leominster, in the county of Worcester and State of Massachusetts, have invented a new, original, and ornamental Design for Hair Ornaments, of which the following is a specification, reference being had to the accompanying drawing, forming part thereof.

The figure is a face view of an article showing my design.

It may be said to comprise a substantially rectangular frame composed of end bars 1, 1 and top and bottom bars 2, 2. Extending from the lowermost corners and curving upwardly toward the center of the structure is a bar or chord 3, while a similar bar or chord 4 extends from the uppermost corners, meeting the lower chord at the center. A second pair of chords 5 and 6 extend from the central portion of each end bar 1, said chords curving respectively up and down and conjoining with the upper and lower bars adjacent to the center thereof.

I claim:

The ornamental design for a hair ornament, as shown and described.

DENNIS A. DRISCOLL.
